MODULAR PUMP HOUSING FOR CARDIOVASCULAR EQUIPMENT

James H. De Vries and Richard N. Sarns, Ann Arbor,
Mich., assignors to Sarns, Inc., Ann Arbor, Mich., a
corporation of Michigan

Filed July 28, 1965, Ser. No. 86,334

Term of patent 14 years

(Cl. D83—1)

FIG. 1

FIG. 2

FIG. 3

FIG. 1 is a perspective view of a modular pump housing for cardiovascular equipment showing my new design.

FIG. 2 is a rear perspective thereof.

FIG. 3 is a side elevational view taken on an enlarged scale.

The dominant features of my design reside in the portions shown in full lines.

We claim:

The ornamental design for a modular pump housing for cardiovascular equipment, as shown and described.
